Primary Examiner — Lauren D McVey*Assistant Examiner* — Sarah L Smith(74) *Attorney, Agent, or Firm* — George D. Morgan(57) **CLAIM**

The ornamental design for a multifunctional camping light, as shown and described.

DESCRIPTION

FIG. 1 is a front, top and left side perspective view of a multifunctional camping light, showing my new design; FIG. 2 is a perspective view of the article in an extended state;

FIG. 3 is a front view of FIG. 1;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the multifunctional camping light, which form no part of the claimed design. The dash-dot-dash broken lines encircling the enlarged views are for reference purposes only and form no part of the claimed design.

1 Claim, 9 Drawing Sheets(56)
